(57) **CLAIM**

The ornamental design for an in-line bottle rack, as shown and described.

DESCRIPTION

FIG. 1 is a perspective view of a free-standing, double-sided in-line bottle rack, showing my design;

FIG. 2 is a perspective view thereof, in use condition;

FIG. 3 is a front view thereof;

FIG. 4 is a rear view thereof;

FIG. 5 is an end view thereof;

FIG. 6 is an opposing end view thereof;

FIG. 7 is a top view thereof; and,

FIG. 8 is a bottom view thereof.

The broken lines showing the environment are for illustrative purposes only and form no part of the claimed design.
